UNITED STATES PATENT OFFICE.

GEORGE W. MATTERN, OF DAYTON, OHIO, ASSIGNOR TO THE CRAWFORD, MCGREGOR AND CANBY COMPANY, OF DAYTON, OHIO, A CORPORATION OF OHIO.

INSERT FOR GOLF CLUBS.

Application filed November 27, 1920. Serial No. 426,703.

To all whom it may concern:

Be it known that I, GEORGE W. MATTERN, a citizen of the United States, residing at Dayton, in the county of Montgomery and 5 State of Ohio, have invented certain new and useful Improvements in Inserts for Golf Clubs, of which the following is a specification.

My invention relates to golf clubs and 10 more particularly to the seating or anchoring of an insert or impact plug in the striking face of the club.

Golf club heads are ordinarily made of wood, which does not afford the requisite 15 rigidity at the point of impact to give the desired distance to the ball, which is the objective of every golfer. For this reason, it has heretofore been the practice to insert in the striking face of the golf club head, a 20 body of characteristically different material. In practice ivory has been found to be the most desirable material for such inserts. Other materials, however, such as fiber, lignum vitæ, ebony, hickory and even certain 25 metallic alloys may be employed. The desired characteristic is not that of affording to the ball a great rebound when struck, but one which while affording the requisite resistance and solidity, will enable the player 30 to "follow thru," thus transmitting to the ball greater force than the mere initial impact.

As heretofore employed, such inserts have been cemented, glued or otherwise secured 35 within bores, or sockets formed within the club head, wherein they have a thrust bearing, only on the bottom of such bore or socket. This results in the force of the impact, being localized at the end of the insert 40 or impact plug, and frequently results in splitting of the head or breaking of the shank or shaft. Moreover, the driving effect of the blow upon the insert or plug, tends to move it axially within its socket 45 thereby loosening its attachment and this loosening effect is aggravated by the relative shrinkage and expansion of the head and insert. The loosening may not be such as to afford any perceptible movement of 50 the insert within the head, yet upon impact with the ball, there will be lacking the feeling of rigidity, and the break or interruption of the vibration will materially affect the flight of the ball.

55 The present invention is designed to over-

come these difficulties by providing an impact plug or insert having screw threaded engagement with the club head, whereby it is not only securely anchored against longitudinal movement under the force of the 60 impact, but the screw threads afford materially increased thrust bearing surfaces, and serve to distribute the vibration thruout the club head, thereby inducing a harmonious action, and obviating the tendency to 65 breakage.

With the above primary and other incidental objects in view as will more fully appear in the specification, the invention consists in the features of construction, the 70 parts and combination thereof, and the mode of operation or their equivalents, as herein-after described and set forth in the claims.

In the drawing, wherein is shown the preferred embodiment of the invention, Fig. 1 75 is a perspective view of a golf club head, showing a single insert or impact plug in the striking face thereof. Fig. 2 is a sectional view of the head showing therein the impact plug or insert forming the subject matter hereof, and illustrating the relative extent of the insert within the body of the head. Fig. 3 is a detail view of the impact plug or insert removed from the golf club head. Fig. 4 illustrates a modification 80 embodying a plurality of inserts or impact plugs, grouped to afford a pleasing design, for the striking face of the club.

Like parts are indicated by similar characters of reference throughout the several 90 views.

Referring to the drawings, 1 is the head 95 of a golf club, which may be of fiber or other suitable material, but which is preferably formed from wood. Inlaid in the striking face 2 of the club head 1, is a face plate 3 of fiber, lignum-vitæ, hard rubber or other suitable material. Inserted into the body of the club head 1, thru the face plate 3 is the impact insert or plug 4, which as 100 before stated is preferably though not necessarily of ivory. The material of the golf club head does not afford a desirable striking surface, particularly in view of the fact that the grain of the wood forming the head 105 extends parallel with the striking face 2. When wood is employed, as an insert or impact plug, it is usually arranged with the grain in the direction of the line of stroke, whereby the impact is received upon the 110

ends of the grain. However, in the present instance, the particular material of the insert plug forms no essential part of the invention, and while ivory is the desirable material, it is to be understood that fiber, wood, hard rubber, or metallic alloys may be employed in lieu thereof.

The impact insert 4 is screw threaded thruout the greater portion of its length 10 as indicated at 5, leaving adjacent to the exterior terminal face an unthreaded portion 6. A counter-bored socket is provided thru the face plate 3, and into the body of the head 1, the larger outer portion of 15 such counter-bored socket extending partially thru the face plate 3, while the smaller or inner portion of such socket, within the body of the head 1, and the remaining portion of the face plate 3 is screw threaded 20 to agree with the threads 5 of the insert. The unthreaded extremity 6 of the insert agrees in diameter with the mouth of the socket formed in the plate 3, wherein it is afforded a uniform tight fit. The insert or 25 plug 4 is screwed into place after having been coated with cement or other adhesive, and the striking surface is finished flush with the face 2 and plate 3. By leaving a portion of the insert or plug cylindrical and 30 devoid of screw threads, a uniform tight joint is afforded between the insert and the face plate. Otherwise, if the screw threads were extended thruout the full length of 35 the insert, the intersection of the plane of the striking face with the screw threads, would afford an irregular and objectionable surface. The interengagement of the threads of the plug or insert, within its socket not only materially increases the 40 thrust bearing of the insert, but it equalizes and distributes the shock of the impact thruout a greater portion of the club head, and induces a harmonious vibration of the head as a whole. The interlocking of the 45 insert with the material of the head by means of the screw thread not only distributes the shock and vibration, but it ties the material of the head and strengthens the head to prevent breakage. It affords an 50 absolutely rigid or solid driving surface, which, however, is not inert. The line of cleavage between the insert or impact plug and the body of the head being unaligned with the direction of the blow, or undulating, resists any tendency of the insert to 55 drive inward, thereby loosening the attachment of the insert and head. Not only does this interlocking resist any longitudinal movement or loosening effect, but in the 60 event of expansion and contraction of the head and insert it will retain its engagement within the head, and will not have the 65 tendency to become loose in its socket. By threading the insert or plug partially in the face plate 3, the latter is rigidly held in posi-

tion upon the club head, and independent vibration or interruption of the vibratory impulses is prevented. Whereas in the ordinary straight or cylindrical insert, the localization of the thrust at the bottom of 70 the socket tends to split the head, the present interlocked or screw threaded construction distributes the strain, and serves to tie the head to prevent such breakage.

While the addition of screw threads, well 75 known for other purposes to an insert or impact plug in a golf club head appears to be but a small thing, it has resulted in a very great and material improvement in 80 the action of the club, and has afforded materially increased distance in the flight of 85 the ball. It affords a firm rigid, but not inert striking face, which will not loosen under severe usage, or expansion and contraction of the material, under which conditions the ordinary form of insert develops 90 an imperceptible looseness or lack of solidity, discernible only in the feel of the club at the moment of impact, and in the interruption of the vibration set up in the club, 95 which, however, does materially effect the flight of the ball. To be screw threaded the inserts or plugs, are of course, necessarily cylindrical. However, these inserts or plugs may be of various sizes and may be arranged 100 in different grouped relation to agree with individual taste. For instance, in Fig. 1 there has been shown a single insert of comparatively large size, while in Fig. 4 there is shown a plurality of smaller inserts 105 grouped to afford in addition to their mechanical function, a design of pleasing appearance.

From the above description it will be apparent that there is thus provided a device 105 of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several 115 modes of putting the invention into effect, and the invention is therefore claimed in any of its forms or modifications within the legitimate and valid scope of the appended claims.

Having thus described my invention, I claim:

1. In a golf club, a head, and a cylindrical insert plug of substantially uniform diameter throughout in the striking face of the 120 125 130

- head, said plug being screw threaded thruout a portion of its length, that portion of the plug adjacent to the striking face being devoid of screw threads, said 5 head having a receiving socket for the plug formed therein said socket being screw threaded thruout a portion of its depth but devoid of threads adjacent to its mouth.
2. In a golf club, a wooden head, a face 10 plate forming the striking surface of the head, and an insert plug set flush in said striking face having screw threaded engagement with both the head and face plate.
3. In a golf club, a head, a screw threaded 15 insert plug of substantially uniform maximum diameter throughout in the striking face of the head, the head of said plug being set flush with the striking face, said head being devoid of screw threads, the 20 golf club head having therein a socket conforming to said insert plug.
4. In a golf club, a wooden head and a cylindrical ivory insert plug in the striking face of the club, said ivory insert plug having screw threaded engagement with the 25 wooden head of the club throughout a portion only of its length whereby the insert plug will present an unbroken terminal face.
5. In a golf club, a wooden head, a face 30 plate on said head, and a screw threaded ivory insert plug extending thru the face plate and having screw threaded engagement with the wooden head.
6. In a golf club, a wooden head, a face 35 plate on the striking face of the head, a screw threaded insert plug extending thru the face plate and having screw threaded engagement with the wooden head, the screw threads of the plug terminating in spaced relation with the terminal face of the insert 40 plug, said face plate having therein an opening conforming to the unthreaded portion of the insert plug.
7. An insert for golf club heads comprising a substantially cylindrical body of 45 ivory or like material, said body being exteriorly screw threaded, the screw threads terminating in spaced relation with one terminal face of the plug to afford a peripheral margin of sufficient depth to avoid 50 breakage.
8. In a golf club, a wooden head and a plurality of substantially cylindrical insert 55 plugs, said plugs being exteriorly screw threaded throughout the greater portion of their length, the threads terminating in spaced relation with the terminal faces, said threaded inserts being arranged in grouped spaced relation in the striking face of the club head. 60

In testimony whereof, I have hereunto set my hand this 9th day of November A. D. 1920.

GEORGE W. MATTERN.
